UNITED STATES PATENT OFFICE.

BLANCA WILL, OF ROCHESTER, NEW YORK.

DESIGN FOR A STOVE-SHELF.

41,445.

Specification for Design.

Patented June 6, 1911.

Application filed March 20, 1911. Serial No. 615,818. Term of patent 14 years.

To all whom it may concern:

Be it known that I, BLANCA WILL, a citizen of the United States, residing at Rochester, in the county of Monroe and State of New York, have invented a new, original, and ornamental Design for Stove-Shelves, of which the accompanying drawing is a representation.

Figure 1 is a perspective view of a stove

shelf embodying my new design, and Fig. 2 is a side elevation thereof.

I claim:

The ornamental design for a stove shelf as herein shown.

BLANCA WILL.
